UNITED STATES PATENT OFFICE.

THEODORE T. WEBER, OF BUFFALO, NEW YORK.

CARBURETER.

1,091,784.

Specification of Letters Patent. Patented Mar. 31, 1914.

Application filed February 13, 1913. Serial No. 748,100.

To all whom it may concern:

Be it known that I, THEODORE T. WEBER, a citizen of the United States, residing at Buffalo, in the county of Erie and State of New York, have invented certain new and useful Improvements in Carbureters, of which the following is a specification.

My invention relates to improvements in carbureters and refers to a carbureter for producing gas from gasoline and other hydrocarbons.

The objects of the invention are the production of a carbureter which will produce a highly efficient gas from gasoline or the like by securing the proper degree of heat and mixture of air; which carbureter will be of compact and small size but have a large carbureting capacity; which will be absolutely reliable and efficient in operation and which will be inexpensive, durable and practical in construction.

In the attainment of the objects stated my carbureter consists of a gasoline tank or chamber, a contiguous hot water chamber, heating and purifying means, and circulating pipes for air and hot water, all combined for service in carbureting air.

The invention further consists of a carbureter embodying novel features of construction, combination and arrangement of parts substantially as illustrated, described, and particularly defined by the claims.

In the drawings I have illustrated a carbureter constructed in accordance with my invention, but I would have it understood that I reserve the right to make any changes in the construction of my carbureter which come within the scope of my invention.

Figure 1 is a central sectional view of the complete carbureter. Fig. 2 is a section on line 2-2, Fig. 1. Fig. 3 is a section on line 3-3, Fig. 1. Fig. 4 is an end view or elevation of the carbureter, and Fig. 5 is a section on line 5-5, Fig. 1.

In the drawings, in which similar numerals of reference denote corresponding parts in all the views:—The numeral 6 designates an outer casing which is of rectangular or any other desired form and of any determined size or capacity. In its top wall this casing is provided with an opening 7, over which is mounted a dome 8, and a partition wall 9 is disposed near its bottom which forms a chamber 10. This construction provides a gasoline container or tank 11, the gas dome 8 which is in direct com-

munication with the tank, and the chamber 10, which as will presently appear, serve as a heat chamber, such heat chamber having air inlets 12 controlled by slides or dampers 13. The gasoline tank is provided with a supply pipe 14, a discharge or draw-off pipe 15, and with safety valves 16, and further with a gage 17 to register the gas pressure in the tank. Entering the casing from the top are auxiliary air-tubes 18 which have their lower ends submerged in the gasoline within the tank 11 and which are provided with spring-retained inwardly-opening valves 19. From this construction it will be noted that the gasoline tank is provided with safety valves which are spring-controlled and open outward and with auxiliary valves which are spring-controlled and open inward, the auxiliary valves controlling the admission of air through the tubes 18.

Within the heat chamber are placed horizontally-disposed hot water or air coils 20, preferably the former, which receive hot water at the connection 21 from an engine 80 or other source, and form a series of six pipes or sections which after occupying the entire heat chamber, pass outward therefrom and then enter the gasoline chamber at 22. The pipe entering this point is continued through the body of gasoline in the tank 11 and has connection with a heater or drum 23 arranged centrally in the tank 11 and terminating at its upper end within the gas dome 8. Connected to the heater or drum at its upper end is a pipe 24 which extends down into the gasoline, thence backward and forward therein and finally cut the tank at 25, for connection with the engine or otherwise, so that the hot water or any other heating medium may be passed therefrom, to be returned to the hot water or air coils 20, at 21. In this manner the heating medium is introduced, passed through the apparatus and returned, if desired, to the engine to be reheated and again delivered through the apparatus. When so used, the cooling water of the engine serves to heat the air and gasoline as well as the mixture in its passage from the apparatus. It is apparent, therefore, that the hot water pipes are disposed in the heat chamber 10, in which there is a high degree of heat generated by the hot water passing through said pipes, and that the hot water pipes after completely circulating in the heat chamber, enter the gasoline tank, and subject the

tire body of liquid to the heat, and then pass into the heater or drum 23 at a low point and out at a high point, thence through the body of gasoline and back to the engine, or otherwise.

5 The heater or drum is disposed vertically in the tank and dome thereof, and is formed with a pair of heads or plates 26 formed each with threaded nipples 27, in which are secured the ends of the vertical pipes 28, forming gas conducting pipes and a surrounding hot water space 29. The heater or drum has a funnel 30 connected to the bottom which has a depending delivery pipe or 10 outlet 31 extending through the heating chamber 10. Said delivery pipe conveys the gas direct to the engine for consumption, and in the funnel is arranged a series of strainers or filters 32 whose purpose is to 15 completely remove any sediment or foreign matter from the gas before entering the engine and also thoroughly mix the vaporized gasoline and air as they pass therethrough.

To insure the production of an explosive 20 mixture I provide two pairs of air supply pipes 34, one pair being at each end of the tank and each pair being connected with a single pipe 33 secured to the bottom of the tank 11 and opening into the heating chamber 10, the pipe 33 extends upwardly from said bottom to a point above the level of the gasoline and is thence directed laterally in opposite directions for connection thereto of the vertical tubes 34.

35 From the foregoing description taken in connection with the drawings, the operation of the generator will be readily understood. Assuming the tank to be supplied with the proper amount of gasoline, the main supply 40 of hot air enters the tank from the heating chamber 10 where it is heated in passing therethrough, it being delivered into the gasoline through the pipes 33 and the two pair of tubes 34. In passing through the 45 gasoline the hot air is thoroughly carbureted and rises to the dome 8 of the generator passing from the dome into the vertical pipes 28 in the heater or drum, and from the latter out through the delivery pipe for 50 use, the gas thus produced may be used for any purpose, but when it is desired to use the same as a power medium to be exploded within an engine the suction created by the engine may at times be more than desirable 55 and may result in too rich a mixture, and for this purpose the auxiliary valves 19 are provided which open when the engine is running at high speed and provide the mixture with a quantity of cold air which passes 60 through the gasoline within the tank and is thus carbureted. The air thus carbureted commingles with the carbureted air having passed through the heating chamber within the tank above the gasoline and while passing 65 through the heater. By employing the

auxiliary valves 19 and the air tubes associated therewith the necessary additional quantity of air is taken into the carburetor when the engine is running at high speed, thus providing any deficiency which the size 70 of the air inlets 12 of the heating chamber or the capacity of the air supply pipes 34 will cause. Moreover, the cold air taken in through the auxiliary valves will not result in so rich a mixture as the carbureted air 75 produced in drawing the heated air through the gasoline, and as the suction becomes proportionately greater as the speed of the engine increases, it is desirable that the mixture be somewhat rarefied. In this manner 80 the engine will at all times be provided with the necessary supply of carbureted air having as near as possible the proper proportion of air and gasoline. The main supply of air and the auxiliary supply pass through 85 the body of gasoline within the tank and to the drum or heater and finally through the delivery pipe attached to said drum or heater.

—It will be observed that my generator insures a perfect circulation and mixture of air with the liquid to produce the gas, and that the generator cannot possibly explode, as the safety valves would act under undue pressure to release the excess pressure.

It will be seen that my generator is of small size but large producing capacity and that it can be easily and cheaply installed or connected, and possesses every requirement demanded in an invention of this character.

Having thus described my invention, what I claim is,—

1. In a carburetor, the combination of a gasoline tank, a drum or heater therein, a heat chamber, heating pipes in the said heat chamber leading into the tank and to said heater, means for supplying air to said heat chamber, and means for leading the air from said heat chamber into said tank, said heater having passages for carbureted air in communication with said tank.

2. In a carburetor, the combination of a tank containing a hydrocarbon liquid and having a dome, a heat chamber, a heater arranged in the tank and projecting into said dome, heating pipes in said heat chamber and tank and in communication with the heater, and air supply means in the heat chamber, tank and heater arranged to direct the air through the hydrocarbon liquid in said tank.

3. In a carburetor, the combination of a casing having a partition to form a liquid tank and a heat chamber, a heater mounted in said liquid tank and having gas supply pipes and a surrounding heat space, and means for supplying heat and air to said heat chamber, liquid tank and heater for producing gas.

4. In a carbureter, the combination of a casing divided to form a liquid tank and a heating chamber, air openings in said heating chamber having controlling means, heating pipes arranged in the chamber and leading to said liquid tank, a heater arranged in said liquid tank in communication with said heating pipes, air supply pipes in said liquid tank in communication with said heating chamber, and auxiliary air pipes having valves and leading to said liquid tank.

5. In a carbureter, the combination of a casing divided to form a heating chamber and a liquid tank, air supply openings in said heating chamber having controlling valves, intake air pipes having valves and entering said liquid tank, safety valves provided in said tank, a heater arranged in said tank, heating means disposed in said heating chamber and communicating with said heater, and air supply pipes leading from said heating chamber to said tank.

6. In a carbureter, the combination of a casing forming a heating chamber and a liquid tank, a dome mounted upon and in communication with said liquid tank; a drum-shaped heater arranged in said tank and dome and having a series of gas conducting pipes and a heat space surrounding said pipes, connection with said heater for carrying the gas to an engine, heating pipes having their main portions located in the heating chamber of said casing and formed with branches leading to the heat space of said drum at its highest point and leaving at its lowest point, air supply pipes leading from said heating chamber into said tank, and auxiliary intake air pipes having controlling valves and leading from the outer air into said tank.

7. In a carbureter, the combination of a heating chamber, a surmounting liquid tank,

a heater disposed in said tank and composed of pipes opening into said tank at their upper ends, a concentrator or funnel at the lower open end of said pipes, a filter in said funnel and a heat space around said pipes, heating pipes leading to and from the said heat-space, and air supply and intake pipes in said tank.

8. A carbureter, consisting of a casing having a gas dome, a liquid tank and a heating chamber, a heater arranged in said tank and dome, a connection leading from said heater to and through said heating chamber, heating pipes arranged in said heating chamber and leading into said tank, said heating pipes being connected to said heater near its top and bottom, air intake pipes in said tank entering from the outer air, and air supply pipes discharging into said tank and receiving air through said heating chambers.

9. A carbureter, consisting of a casing having a gas dome, a liquid tank and a heating chamber, a heater arranged in said tank and dome, a connection leading from said heater to and through said heating chamber, heating pipes arranged in said heating chamber and leading into the tank, said heating pipes being connected to said heater near its top and bottom, air intake pipes in the tank entering from the outer air, and air supply pipes discharging into the tank and receiving air through said heating chambers, said air supply pipes having each a pair of downward extending branches.

In testimony whereof, I have affixed my signature in the presence of two subscribing witnesses.
